(Cl. D34—15)

To all whom it may concern:

Be it known that I, Elmer J. Firquain, a citizen of the United States, residing at Kansas City, in the county of Wyandotte and State of Kansas, have invented a new, original, and ornamental Design for Coasters, of which the following is a specification, reference being had to the accompanying drawing forming part thereof, in which:

Fig. 1 is a side elevation of a coaster, showing my new design.

Fig. 2 is a plan view.

Fig. 3 is a front elevation.

I claim:

The ornamental design for a coaster, as shown.

ELMER J. FIRQUAIN.
